MOTOR MOUNTING BRACKET

David Lane, Philadelphia, Pa., assignor to Progress Manufacturing Company, Inc., Philadelphia, Pa., a corporation of Pennsylvania

Application February 18, 1955, Serial No. 34,572

Term of patent 14 years

(Cl. D26—5)

Fig. 1

Fig. 2. Fig. 3.

Figure 1 is a front perspective view of a motor mounting bracket showing my new design thereof;

Figure 2 is a rear elevational view thereof; and
Figure 3 is a side elevational view thereof.

I claim:

The ornamental design for a motor mounting bracket, as shown.
